UNITED STATES PATENT OFFICE.

ERASTUS E. WINKLEY, OF LYNN, MASSACHUSETTS.

SHOE-SEWING MACHINE.

SPECIFICATION forming part of Letters Patent No. 624,599, dated May 9, 1899.

Application filed June 5, 1897. Serial No. 639,628. (No model.)

To all whom it may concern:

Be it known that I, ERASTUS E. WINKLEY, a citizen of the United States, residing at Lynn, in the county of Essex and State of Massachusetts, have invented certain new and useful Improvements in Shoe-Sewing Machines; and I do hereby declare the following to be a full, clear, and exact description of the invention, such as will enable others skilled in the art to which it appertains to make and use the same.

The present invention relates to improvements in shoe-sewing machines, and more particularly to certain improvements in that type of shoe-sewing machines which unite the welt to the lasted upper and inner sole and generally known as "welt" machines. Heretofore machines of this class have generally been of the chain-stitch type for the reason that much difficulty has been found in adapting a lock-stitch machine for this work. It is essential that the welt and upper be drawn tightly against the shoulder or "lip" of the insole, and in the lock-stitch machines of the prior art much difficulty has been encountered in adapting lock-stitch mechanism to this class of work, for the reason that it has been extremely difficult to regulate the tension to properly draw in against the shoulder or lip, the upper, and welt and to correctly position the lock in the between substances. If the shuttle tension be too great, the lock will be left too near the outside of the between substances and the stitch will be loose, and if the tension of the shuttle-thread be too light the lock will be drawn through the between substances, also leaving a loose stitch.

In a former application, filed by me March 26, 1897, Serial No. 629,411, I have shown and described a machine which is adapted to unite the welt, upper, and insole by a lock-stitch and which is designed to overcome the difficulties above set forth, and the present invention relates to certain improvements on said machine. In said machine as the supply-thread take-up acts to draw on the supply-thread to set the stitch the shuttle-thread is locked or the tension is increased thereon, and a shuttle-thread-measuring device is employed which measures off from the shuttle the amount of thread required for a stitch, and the tension on both the supply and shut-

tle threads is properly regulated and controlled to accurately set the stitch and position the lock in the between substance. In the present machine the shuttle-thread-measuring device is omitted and the shuttle is constructed and arranged to have a movement toward and from the work to measure or pull off the shuttle-thread for the stitch, and a take-up device acting on the shuttle-thread cooperates with the supply-thread take-up in setting the stitch.

The present invention consists of the devices and combination of devices which will be hereinafter described and claimed.

The invention is shown in the accompanying drawings, in which—

Figure 1 is a side view of a welt-sewing machine embodying a preferred form of the present invention, a portion of the frame being broken away to show underlying parts and the supporting-column omitted. Fig. 2 shows in side elevation the shuttle mechanism and the shuttle-thread take-up. Fig. 3 shows the same parts in plan view, and Fig. 4 shows a fragmentary detail of the shuttle-driving mechanism.

Similar letters of reference refer to similar parts throughout the several views.

In the drawings, A represents the head or frame suitable to support the working parts of the machine and which may be conveniently mounted upon the usual supporting column or standard. (Not shown.) The head A is provided with the usual standards a, (one only being shown,) on which are provided suitable bearings for the main shaft B, which carries a series of actuating-cams (one only being shown) and which will be hereinafter called the "cam-shaft" and to which power may be applied in any convenient manner.

D represents the needle, mounted upon the needle-segment d, pivoted at d' to a fixed part d² of frame A, and actuated by a link d⁴, pivoted at d³ to the needle-segment, and at its rear end pivotally connected at d⁵ to one arm d⁶ of a lever fulcrumed upon the shaft B' and actuated by a cam and connections (not shown) from the cam-shaft B.

The above-described arrangement is such that a rotation of the cam-shaft B, will, by means of the cam and connections, (not shown,) actuate the arm d⁶ of the lever ful-

crummed upon shaft B', and impart a motion of reciprocation to the link d⁴, which oscillates the segment d about its center d', causing the needle D to be advanced and retracted along 5 a circular path.

E represents the looper, which may be actuated in any suitable manner to impart thereto a movement toward and from the needle D in a circular path to place the needle-thread in the hook thereof.

F represents the supply-thread measurer, which preferably has a swinging or oscillating movement in such manner that when it has engaged the thread it is carried upward 15 and outward toward the medial line of the sole, as fully described in my pending application hereinbefore referred to.

T represents the supply-thread take-up, mounted on a take-up lever t, fixed to the end 20 of a short shaft t', upon which is fixed a segmental pinion t³, with which engages a segmental rack t⁴, carried by an arm t⁵ of a lever t⁶, fulerumed on an arm a⁹ on the standard a and actuated by a cam (not shown) on the 25 cam-shaft B.

P represents the welt-guide, which may be of any usual or convenient construction, mounted upon an arm p, rigidly secured to the feed-slide p', said feed-slide being mounted 30 to reciprocate in a guideway p³, formed in a block p⁵, fixedly secured to a fixed portion of the frame or head A.

C represents the channel-guide, which is properly curved and shaped at its lower end 35 to engage the channel of the shoe-sole and is arranged to have a movement toward and from the welt-guide P to clamp and release the work and a lateral feeding movement with the welt-guide to feed the work.

40 All of the foregoing elements may in so far as the present invention is concerned be of any usual or preferred form and arrangement and actuated by any suitable or convenient means to cause them to perform the functions which 45 they are designed to perform. For convenience they are illustrated in Fig. 1 as they appear in the application hereinbefore referred to; but while said arrangement is preferred it is not essential to the present invention, it being only necessary that the parts shall be timed and arranged to perform the usual function of such devices in machines 50 of this character.

In the present machine, as in the machine 55 of the application referred to, the welt-guide P preferably has no movement toward and from the work, but is fixed rigidly so that it will form a back gage against which the work may be pressed and against which it is locked 60 by the channel-guide during the movement of the channel-guide and welt-guide along the line of feed to feed the work.

H represents the shuttle, which may be arranged to oscillate or rotate in a suitable shuttle-race h, the shuttle being actuated in said race by a shuttle-driver h', having a projection 65 which engages the shuttle between the

hook and heel in the usual manner. The shuttle-driver h' is mounted in a bracket h¹⁰, affixed to the shuttle-race h, and is actuated 70 by a short shaft h², which is fixed in a bearing h³, carried by an arm h⁴, secured in a fixed position upon the frame A. Upon the shaft h², outside of the bearing h³, is a pinion h⁵, which may be driven by any suitable means 75 to impart an oscillatory or rotary movement to the shuttle-driver h'. As shown in dotted lines in Fig. 1 of the drawings, said pinion h⁵ is engaged by a segment-gear h⁶, carried by a lever h⁷, fulerumed upon the shaft B' 80 and actuated by a cam (not shown) upon the cam-shaft B, so arranged that the shuttle-driver h' will be oscillated and impart an oscillating motion to the shuttle H.

In the present invention the shuttle H is 85 given a longitudinal reciprocating movement in order to draw off or measure off the shuttle-thread for a stitch, and to provide for this movement of the shuttle there is a movable connection between the shaft h² and the shuttle-driver h', the shuttle-driver partaking of the movements of the shuttle H. Any suitable connection may be employed between the shuttle-driver h' and the shaft h² which will permit the movement of the shuttle-driver 90 out of alinement with the axis of the shaft h² and which will insure the operative and correct engagement thereof to actuate the shuttle when the shuttle-driver shall have been moved forward to again position the shuttle-driver h' in alinement with the shaft h². In the machine of the drawings the connection between the shuttle-driver h' and the shaft h² consists of a disk h⁶, secured to the shuttle-driver h', and a disk h⁷, secured to the 105 end of the shaft h², the disk h⁶ having a diametrical rib h⁸, which engages a diametrical groove h⁹ in the disk h⁷, the construction being such that the shuttle-driver h' is always maintained in operative connection with the shaft h² as the shuttle-driver h' moves backward with the shuttle H.

To provide for the forward-and-backward movement of the shuttle, the shuttle-race h is mounted upon a carrier H', which is adapted to be reciprocated along a guideway H², formed in or on the frame A, said carrier H' being moved along said guideway H² by a lever H³, which is fulerumed upon the shaft B' and at its upper end engages a cam B⁴ on the cam-shaft B and at its lower end is pivotally connected at b to a short link b', which in turn is pivotally connected at b² to the carrier H'. The above-described arrangement is such that a rotation of the cam-shaft B will, by means 125 of the cam B⁴ thereon, oscillate the lever H³ and impart to the carrier H' a reciprocating movement along the guide H², thus moving the shuttle H back and forth toward and from the work, the backward movement acting to 130 pull from the bobbin h¹¹ in the shuttle the amount of shuttle-thread required for the next stitch.

In the present invention there is provided

a shuttle-thread tension device, which is so constructed and arranged that upon a retraction of the shuttle the tension on the shuttle-thread is released, so that it may be drawn therefrom, and upon a forward or outward movement of the shuttle the tension on the thread will be increased in order that it may be held from being drawn out during the action of the shuttle-thread take-up.

10 As shown in the accompanying drawings, the lead of the shuttle-thread w is across the face of the bobbin h^{11} , the bobbin being provided with a groove h^{12} , (see dotted lines, Fig. 2,) and is preferably otherwise constructed 15 like the bobbin of the machine of the application referred to and has a tension-spring which fits in said groove h^{12} and bears upon the shuttle-thread w , passing beneath the same, a portion of the tension-spring projecting 20 from the groove h^{12} and the face of the bobbin, whereby it may be engaged by a tension-regulating device, whereby the tension or the shuttle-thread may be varied upon the backward-and-forward movements of the 25 shuttle, as described. This tension-regulating device in the machine of the drawings comprises a lever N , which is fulcrumed at n on a shaft n' , mounted in a bearing n^3 , carried by the slide or carrier H' , and at its outer end 30 n^3 is suitably formed to act upon the projecting portion of the tension device carried by the bobbin. A movement of the end n^3 toward the face of the bobbin and shuttle will cause the end n^3 to bear upon the tension device and increase the tension on the shuttle-thread, and a movement of the end n^3 away from the face of the bobbin and shuttle will release the pressure on the tension device and relieve the tension thereof on the shuttle-thread in order that said shuttle may give up its thread as it is moved backward, as hereinbefore described. The lever N is actuated to move its end n^3 toward and from the 35 face of the shuttle and bobbin by means of a lever N' , which is fulcrumed on the shaft n' and which extends each side of its fulcrum, the forward end n^4 being connected with the lever N and the opposite end n^5 being arranged to bear upon a portion of the fixed 40 frame A , adjacent the guideway H^2 , it being held in contact therewith by a coiled spring n^6 , one end of which is connected to the end n^5 of the lever N' and the opposite end to some fixed portion of the frame A . In 45 the frame A , adjacent the guideway H^2 , against which the end n^5 of the lever N' is held by the spring n^6 , is formed a cut or notch n^7 , into which the end n^5 is adapted to be drawn during its backward movement by the spring n^6 50 to cause the forward end n^3 of the lever N to move away from the face of the shuttle and bobbin.

The above arrangement is such that a forward movement of the slide H' and the shuttle H thereon will carry forward the lever N' and move the end n^5 thereof out of the notch

n^7 , thus throwing in the end n^4 , which is connected to the lever N and causing the end n^3 of the lever N to bear forcibly upon the tension device of the bobbin to increase the tension on the shuttle-thread and prevent its being drawn out of the shuttle, and upon a backward movement of the slide H' the end n^5 of the lever N' will be drawn into the notch or recess n^7 by the action of the spring n^6 , thus 75 throwing out the end n^3 of the lever N and relieving the pressure on the tension device, permitting the shuttle-thread to be drawn off upon the backward movement of the shuttle. The position of the notch or recess n^7 is such 80 that it acts upon the lever N' to lock the shuttle-thread just after the loop of needle-thread has passed the center of the shuttle as it is being carried around the shuttle by the oscillation thereof. At the time the shuttle has 85 reached its advanced position and while the needle-thread take-up T is acting upon the needle-thread to set the stitch the shuttle-thread is acted upon by a take-up which cooperates with the needle-thread take-up in 90 properly tightening the stitch and positioning the lock of the stitch in the between substance.

In the machine of the drawings the shuttle-thread take-up is shown as a stud S , which 95 projects from one side of a bent arm s of a bell-crank lever, which is pivotally mounted upon a stud s' , carried by the end n^3 of the lever N , the other arm s^2 of the bell-crank lever being pivotally connected at s^3 to a link 100 s^4 , which in turn is pivoted at s^5 to one arm s^6 of a bell-crank lever which is fulcrumed at s^7 to the slide H' , the other arm s^8 of said bell-crank lever being pivotally connected at s^9 to a link s^{10} , link s^{10} being in turn pivotally connected at s^{11} to a lever s^{12} , fulcrumed to a shaft B^2 and engaging by its outer end a cam-groove (not shown) in the face of the cam B^4 on the cam-shaft B .

The above-described arrangement is such 110 that a rotation of the cam B^4 will, by means of the lever s^{12} and link s^{10} , oscillate the bell-crank lever s^8 and s^6 about its fulcrum s^7 and draw back the link s^4 , thus oscillating the bell-crank s and s^2 and causing the arm s thereof 115 to be moved in a curved path downward and backward, causing the take-up S to engage the shuttle-thread w and exert a pull upon the same, it being understood that said take-up S is actuated when the shuttle is advanced 120 to its forward position, at which time the shuttle-thread w is locked by the tension device, as before explained. It follows, therefore, that inasmuch as one end of the shuttle-thread w is in the work and the other end 125 locked the take-up S acts upon the same between two fixed points and can exert the proper pull thereon to coöperate with the needle-thread take-up T in setting the stitch.

In order to provide for the ready insertion 130 and removal of the bobbin h^{11} from the shuttle H , the lever N is arranged to swing out-

wardly away from the face of the shuttle upon the shaft n' , and the end n^4 of the lever N' is operatively connected with said lever N by a pin or bolt w' , which fits in a bearing w^2 in the end of lever N' and engages an aperture (not shown) in the lever N , and the link s^4 is made in two sections, hinged together at w^{20} , in vertical alignment with the shaft n' , so that the said lever N and the forward portion of link s^4 may be swung around away from the face of the shuttle whenever it becomes necessary to remove or replace a bobbin therein.

The operation of the machine of the drawings may be described as follows: The channel-guide and welt-guide having fed the work and the needle D having been forced through the between substances and the looper having thrown the loop of needle-thread around the needle, as the needle recedes it draws up the loop of needle-thread in position to be engaged and removed therefrom by the hook on the shuttle. When the needle D reaches the position shown in Fig. 1, the shuttle H is advanced to the position shown in said figure by the advance movement of the carrier H' , and said shuttle being oscillated the loop of needle-thread pulled up by the needle is removed therefrom by the hook of the shuttle and by the movement thereof carried around the shuttle. When the needle-thread passes the center of the shuttle, the continued forward movement of the carrier H' has caused the end n^5 of the lever N' to move out of the notch n^7 , thus throwing the end n^3 of the lever N against the tension device of the bobbin h^{11} , and locked the shuttle-thread. The needle-thread is now acted upon by the take-up T to pull in the loop of needle-thread to set the stitch at the same time the shuttle-thread take-up S is moved downwardly by the lever s^{10} , bell-crank s^8 and s^6 , and link s^4 and engaged the shuttle-thread w , exerting a pull thereon, thus co-operating with the needle-thread take-up in setting the stitch, drawing the upper and welt up closely to the lip and properly positioning the lock in the between substances. When the stitch has been properly set, the channel-guide and welt-guide are moved backwardly preparatory to feeding the work, during which time the slide H' is retracted, permitting the spring n^6 to draw the end n^5 of the lever N' into the notch n^7 , thus throwing outward the end n^3 of the lever N , releasing the shuttle-thread tension device and permitting the shuttle-thread to be drawn off in the further backward movement of the shuttle.

Having fully described my invention and its mode of operation, I claim as novel and desire to secure by Letters Patent of the United States—

1. In a shoe-sewing machine, the combination with a stitch-forming mechanism comprising a shuttle and a supply-thread take-up, of a shuttle-thread take-up independent of the shuttle, and means to actuate the same to cause it to engage the thread between the

shuttle and the work, substantially as described.

2. In a shoe-sewing machine, the combination with a stitch-forming mechanism, comprising a circularly-movable shuttle, and a shuttle-driver, of a shaft for actuating said shuttle-driver and shuttle, connections between the shaft and the shuttle-driver permitting the shuttle to be moved into and out of axial alignment with said shaft and means for so moving the shuttle, substantially as described. 70 75

3. In a shoe-sewing machine, the combination with a stitch-forming mechanism comprising a shuttle and a shuttle-thread tension device, of a shuttle-thread take-up located adjacent to and independent of the shuttle and means to increase the tension of said tension device to lock the shuttle-thread during the action of the shuttle-thread take-up, substantially as described. 80 85

4. In a shoe-sewing machine, the combination with a stitch-forming mechanism comprising a shuttle and means to impart to said shuttle its loop-engaging movement and means to move said shuttle bodily toward and from the needle, of a shuttle-thread tension device, and means to vary the tension of said tension device upon the movement of the shuttle toward and from the needle, substantially as described. 90 95

5. In a shoe-sewing machine, the combination with a stitch-forming mechanism comprising a shuttle, and means to impart to said shuttle its loop-engaging movement and means to move said shuttle bodily toward and from the needle, of a tension device and means to increase the tension of said tension device upon the forward movement of the shuttle, and to relieve the tension of said tension device upon a backward movement of said shuttle, substantially as described. 100 105

6. In a shoe-sewing machine, the combination with a stitch-forming mechanism comprising a shuttle and means to impart to said shuttle its loop-engaging movement, and a reciprocating carrier upon which said shuttle is mounted arranged to move the shuttle toward and from the needle, of a shuttle-thread tension device, and means connected with said carrier for controlling the operation of the tension device, substantially as described. 110 115

7. In a shoe-sewing machine, the combination with a stitch-forming mechanism, comprising a shuttle and means to impart to said shuttle its loop-engaging movement, and a reciprocating carrier upon which said shuttle is mounted arranged to move the shuttle toward and from the needle, of a shuttle-thread tension device, a lever mounted upon said carrier and movable toward and from said shuttle to vary the tension of said tension device, and means controlled by the reciprocation of said carrier to actuate said lever, substantially as described. 120 125 130

8. In a shoe-sewing machine, the combination with a stitch-forming mechanism com-

prising a shuttle, of a shuttle-thread take-up located adjacent to and independent of the shuttle arranged to engage the shuttle-thread between the shuttle and the needle, substantially as described.

9. In a shoe-sewing machine, the combination with a stitch-forming mechanism comprising a shuttle, of a shuttle-thread take-up located adjacent to and independent of the shuttle, a shuttle-thread tension device, and connected mechanism operating automatically to increase the tension on the shuttle-thread to lock such thread during the operation of the shuttle-thread take-up, substantially as described.

10. In a shoe-sewing machine, the combination with stitch-forming mechanism comprising a shuttle and means to move the same toward and from the needle, of a shuttle-thread take-up movable with said shuttle toward and from the needle, said take-up being located adjacent to and independent of the shuttle, substantially as described.

11. In a shoe-sewing machine, the combination with a back gage or rest for the work held from motion transversely to the line of feed of the work, of a shuttle, and means to advance and retract said shuttle toward and from the working end of the fixed gage, a shuttle-thread tension device and means actuated by the reciprocations of the shuttle to

vary the tension of the shuttle-thread tension device, substantially as described.

12. In a shoe-sewing machine, the combination with a stitch-forming mechanism comprising a shuttle, means to impart to said shuttle its loop-engaging movement and means to move said shuttle toward and from the needle, of a shuttle-thread take-up independent of the shuttle, and means to cause it to engage the shuttle-thread when the shuttle is in its advanced position, substantially as described.

13. In a shoe-sewing machine the combination with a needle and shuttle, means to move the shuttle toward and from the needle and means to impart to said shuttle its loop-engaging movement, of a shuttle-thread take-up normally disengaged from the thread movable with said shuttle in its movements toward and from the needle, and means to actuate said take-up upon a movement of the shuttle toward the needle to cause said take-up to engage the shuttle-thread and exert a pull thereon, substantially as described.

In testimony whereof I affix my signature in presence of two witnesses.

ERASTUS E. WINKLEY.
